Attorneys

UNITED STATES PATENT OFFICE.

ALFRED RUCKSTAHL, OF DETROIT, MICHIGAN, ASSIGNOR TO HOLCROFT & CO., OF DETROIT, MICHIGAN, A CORPORATION OF MICHIGAN.

ELECTRIC FURNACE.

Application filed May 11, 1922. Serial No. 560,187.

To all whom it may concern:

Be it known that I, ALFRED RUCKSTAHL, a citizen of the United States of America, residing at Detroit, in the county of Wayne 5 and State of Michigan, have invented certain new and useful Improvements in Electric Furnaces, of which the following is a specification, reference being had therein to the accompanying drawings.

10 This invention relates to electric furnaces especially designed for the heat treatment of relatively small objects at high temperatures.

15 It has for its object to provide an arrangement of electric resistance elements in which variations of temperature may readily be made without the removal or alteration of parts and in which the resistor unit is readily removable to permit the substitution therefor of interchangeable units having different heat characteristics whereby great variations in temperature may be obtained with a minimum loss of time.

20 A further object of the invention is to provide a form of electric resistance unit in which insulating means is provided for the electric resistance element or elements, the insulating means consisting of a refractory substance provided with a supporting framework consisting of a metallic alloy highly resistant to heat and oxidation whereby a rigid metallic structure will prevent or lessen the likelihood of fracture of the refractory elements so that in the operation 25 of inserting and removing the resistor units the danger of breakage will be reduced to a minimum.

30 Other objects will appear in connection with the description, reference being had to the accompanying drawing, in which—

Figure 1 is a longitudinal section through a furnace shown more or less diagrammatically;

Fig. 2 is a transverse section therethrough;

Fig. 3 is a fragmentary detail showing the manner in which a resistance element is secured within the refractory insulating member, and

Fig. 4 is a diagram showing a typical wiring system.

The furnace will consist of any suitable insulating wall 1 surrounding an inner chamber 2 provided with a refractory lining 3 having a doorway 4 which may be

provided with any suitable closure (not shown). Within the chamber 2 a floor 5 is mounted, the floor preferably being of a metallic alloy highly resistant to heat and oxidation.

Through the side wall of the furnace and through the refractory lining, openings 6 and 7 are formed, said openings being provided with closures 8 and 9 of any suitable material. The openings are of a size to permit the ready insertion and removal therethrough of the resistor elements 10. These elements consist of side bars 11 which may be of the configuration shown in cross section in Fig. 1, the vertical flanges of these metallic elements being formed at intervals with webs 12 arranged in pairs to receive therebetween transverse bars 13 of a refractory material such as alundum. The members 11 may be connected preferably near each end by transverse strips 14 preferably of the same alloy as that used for the members 11, the strips 14 being welded or otherwise secured to side members 11 to form a rigid frame.

The refractory insulating members 13 have a series of perforations 15 through which extend the electric resistance coils 16. These coils are preferably arranged as shown diagrammatically in Fig. 4. The perforations 15 as indicated in Fig. 1 are arranged at three different distances from one edge of the insulator bar 13, and an element 16 passing through one of the perforations in the end bar, is bent upon itself as indicated at 17 and returned through the adjacent hole in the same horizontal plane. Such a coil will thus extend in substantially hairpin-shape from one end of the framework to the other as indicated in Fig. 2, and all of the looped resistance members in each horizontal plane will preferably be arranged in series as indicated in Fig. 4. There will be as many series as there are horizontal rows of perforations in the bar 13 and these series may be arranged by suitable switches to be connected in parallel as shown in Fig. 4.

By throwing the appropriate switches 18, 19 or 20 the resistor elements in any plane may be thrown into circuit so that any series or any combination of series may be used without interference with those not in the circuit. As shown in Fig. 1, the heating elements will be arranged above and below the

floor 5 so that heat may be supplied to the chamber 2 in the embodiment herein illustrated by many different combinations of heating elements, thus permitting considerable variation of heat conditions and temperatures without removal of the heating units.

To obtain other heating conditions it will merely be necessary to remove the closure members 8 or 9 whereupon one of the elements may be withdrawn through the opening 6 or 7 and another element substituted therefor having different heat characteristics. The closure will then be replaced and the furnace will again be ready for operation. Additional insulating means 21 and 22 may be placed upon the outer wall of the furnace opposite the openings 6 and 7 if desired.

20 Certain details of the present invention are also described in my co-pending application, Serial No. 560,186 filed concurrently herewith.

It will be obvious that many changes and modifications may be made in the details of the structure herein illustrated without departing from the principle of my invention. The invention is therefore claimed in any of its forms or modifications within the legitimate and valid scope of the appended claims.

I claim:

1. A removable heating unit for an electric furnace wherein the furnace is operative under temperature values usable in the heat treatment of metallic objects, said element comprising a supporting framework of a heat resisting and substantially non-oxidizing alloy, refractory insulating members carried by said framework, and a plurality of electric resistance elements supported by said insulating members.

2. A structure as in claim 1, in which the electric resistance members are adapted for independent removal from, and insertion into, the refractory insulating members bodily.

3. A structure as in claim 1, in which the refractory insulating members are provided with spaced series of perforations arranged at different distances from their edges whereby when the electric resistance members are in place within the perforations there are formed a plurality of layers of heating elements in different planes, the arrangement being such that the heating elements in each plane may be independently brought into an electric circuit.

4. As a means for producing variable heat conditions within an electric furnace operated at high temperature usable in the heat treatment of metallic objects, a chamber having a surrounding wall adapted for the sup-

port of said heating units, said wall having a series of openings therethrough adapted for the insertion and removal of heating elements, and a series of interchangeable electric units of different heating characteristic adapted for insertion through said openings, said electric resistance units being provided with a plurality of independent electric resistance members adapted for independent connection with an electric circuit.

5. A heating element for an electric furnace wherein the furnace is operative under temperature values usable in the heat treatment of metallic objects, said element comprising side bars of an alloy highly resistant to heat and oxidization, said side bars being formed with a plurality of webs, refractory insulating members spanning the space between said side bars and supported thereby, the said webs maintaining the refractory members in position, and a plurality of independent electric resistance members carried by said insulating members.

6. A heating element for an electric furnace wherein the furnace is operative under temperature values usable in the heat treatment of metallic objects, said element comprising a supporting framework carrying transverse refractory insulating members, said insulating members being provided with a plurality of perforations, and a plurality of electric resistance members threaded through said perforations.

7. A heating element for an electric furnace wherein the furnace is operative under temperature values usable in the heat treatment of metallic objects, said element comprising an open metallic framework of an alloy highly resistant to heat and oxidation, said framework being provided with webs on opposite sides thereof, refractory insulating members in engagement with said webs and extending across the open framework, said refractory insulating members having a plurality of perforations arranged at substantially equal intervals throughout their length, and a plurality of electric resistance members passing through the perforations in said insulating members forming a series of substantially parallel runs longitudinally of the heating element.

8. A structure as in claim 7, wherein the electric resistance elements and their terminals are connected in a plurality of groups, each group being adapted for independent connection with an electric circuit.

In testimony whereof I affix my signature in presence of two witnesses.
